US0D1103520S

(12) **United States Design Patent** (10) **Patent No.:** **US D1,103,520 S**
(45) **Date of Patent:** **** Nov. 25, 2025**

(54) **DUST COLLECTOR**

(71) Applicant: **Huang Yi**, Zhuzhou (CN)

(72) Inventors: **Huang Yi**, Zhuzhou (CN); **Xiongfei Liu**, Shenzhen (CN)

(73) Assignee: **Huang Yi**, Zhuzhou (CN)

(**) Term: **15 Years**

(21) Appl. No.: **29/996,800**

(22) Filed: **Apr. 2, 2025**

(30) **Foreign Application Priority Data**

Jan. 17, 2025 (CN) 202530031205.5

(51) **LOC (15) Cl.** **15-05**

(57) **CLAIM**

The ornamental design for a dust collector, as shown and described.

DESCRIPTION

FIG. 1 is a front perspective view of dust collector, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the dust collector that form no part of the claimed design.

1 Claim, 8 Drawing Sheets
